CLAIM

The ornamental design for a frame-hanger-to-frame-hanger tie-plate, as shown and described.

DESCRIPTION

FIG. 1 is a top, front, right side perspective view of a frame-hanger to frame-hanger tie-plate showing our new design; FIG. 2 is a bottom, rear, left side perspective view thereof; FIG. 3 is a top plan view thereof; FIG. 4 is a bottom plan view thereof; FIG. 5 is a right side elevational view thereof; FIG. 6 is a left side elevational view thereof, the right side elevational view being a mirror image thereof; FIG. 7 is a rear elevational view thereof; and, FIG. 8 is a front elevational view thereof.
